UNITED STATES PATENT OFFICE.

JOSEPH DEVLEMINCK, OF HAL, BELGIUM.

FINISHING MACHINE FOR BOOTS OR SHOES.

Application filed March 18, 1925, Serial No. 16,351, and in Belgium March 31, 1924.

This invention relates to a finishing machine for use in the foot wear industry in general and more particularly to machines for rasping soles fitted with recessed or 5 Louis XV heels.

Hitherto the rasping tool has been mounted on the end of a shaft which receives directly a rotary movement by means of a driving pulley; this method of mounting the 10 rasping tool at the end of a comparatively lengthy shaft does not however enable the part of the sole which is attached to the heel to be rasped; in fact, the shaft prevents the boot or shoe being given the necessary inclination for this operation.

By this invention this disadvantage is avoided by mounting for this purpose the rasping tool on a shaft of reduced length to allow contact of the tool with the whole sole.

20 The short shaft is offset relatively to a driving shaft and driven therefrom by the intermediary of a gearing, a pulley or other means. The length of the rasp carrying shaft and the formation of its supporting 25 bearings are such that the boot or shoe may be turned and inclined so that the whole edge of the sole fitted to the heel may be operated on by the said tool.

The accompanying drawing illustrates 30 more or less diagrammatically as an example, a machine constructed in conformity with this invention.

Referring to this drawing, 1 is the frame of the machine, 2 the upper part of this frame 35 which serves at its two ends as a bearing for a horizontal shaft 3. The latter carries in the usual way the loose and driving pulleys 4¹, 4², and on the other end of this shaft 3 a toothed wheel 5¹ is mounted which gears with a 40 wheel of smaller diameter 5² keyed on a short shaft 6, one end of which extends beyond the frame and carries the rasping tool 7. The toothed wheel 5¹ as well as the toothed wheel 5² are mounted in a sheath 2¹ which forms a 45 part of the frame 2 and which serves at the same time as a supporting bracket for the short shaft 6.

The total width of the toothed wheel 5², of

the rasp 7 and of the sheath 2¹ is sufficiently reduced to allow of the edge of the sole along 50 the heel of the boot or shoe 8 being worked on by the tool 7 along its whole periphery, even along the line of connection 8¹ with the sole. The length between the sheath 2¹ and the frame 1¹ must be large enough to allow 55 the boot or shoe to be able to be inclined in such a way that the line 8¹ of the boot is reached by the tool 7 without the toe of the boot or shoe encountering the frame 1¹.

It is evident that the way in which the 60 rotary movement is transmitted to the shaft 6 which carries the tool may be varied according to the maker's wish; this transmission may be effected by means of gearing, or by means of pulleys or the like, but it is always 65 necessary to reduce the length of the shaft 6 sufficiently to allow the tool 7 to have access to the connecting surface between the heel and the sole.

Similarly the form of the frame and that 70 of the sheath 2¹ and of other details of construction and mounting may be varied without thereby departing from the scope of this invention.

I claim:

A machine for rasping the soles of boots or shoes having recessed or Louis XV heels, comprising an upright standard, a horizontally disposed tubular bar mounted on the upper end thereof, a driving shaft in said 80 tubular bar, a vertically disposed bracket on one end of said bar having a downwardly disposed portion extended below the bar, a bearing in the downwardly disposed portion of said bracket, a short shaft supported in said 85 bearing, means for driving the short shaft from the drive shaft, and a rasping tool provided with a toothed periphery carried by the outer end of said short shaft adapted because of its mounting for engagement with 90 the peripheral portions of the soles operated upon including those portions disposed at the heel ends thereof.

In testimony whereof I affix my signature.

JOSEPH DEVLEMINCK.
